IGNITION APPARATUS

Tullio Tognola, Sidney, N. Y., assignor to Bendix Aviation Corporation, New York, N. Y., a corporation of Delaware

Application May 28, 1943, Serial No. 488,850

8 Claims. (Cl. 175—361)

1

This invention relates to ignition apparatus for internal combustion engines and more particularly to a voltage transformer adapted for use in such a system.

One of the objects of the present invention is to provide a novel ignition coil adapted for use in a low tension distribution system wherein the voltage is stepped up at a coil located adjacent the spark plug.

Another object of the invention is to provide a novelly constructed core and coil assembly and a method for making the same.

Still another object is to provide a novel high tension terminal connection for an encased ignition coil.

A further object is to provide a novelly housed ignition coil and novel means for securing the same to an engine.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being primarily had to the appended claims.

In the drawings, wherein like reference characters refer to like parts throughout the several views,

Fig. 1 is a side elevation view, mostly in section and with parts broken away, illustrating one form of ignition coil embodying the features of the present invention, the section being taken substantially on line 1—1 of Fig. 2;

Fig. 2 is an end view of said coil as viewed from the bottom in Fig. 1;

Fig. 3 is an enlarged scale detail view, partly in section and with parts broken away, showing a portion of the novel high tension terminal for the coil of Fig. 1; and,

Fig. 4 is a detail view showing one form of the core for the coil of Fig. 1.

The single embodiment of the invention illustrated in the accompanying drawings, by way of example, is in the form of a housed transformer coil unit particularly adapted for use in a low voltage distribution ignition system for an internal combustion engine, that is, in a system where the current is distributed at its generated voltage and stepped up to sparking voltage at a transformer near each spark plug. As shown, the primary and secondary windings of a transformer coil 10 are concentrically wound and surround

2

one side or arm 11 of a novel laminated rectangular core 12, which will be more fully described hereinafter. The coil windings are preferably surrounded by an insulated casing 13 and it, in turn, is encased in a novel manner by a rigid metallic housing consisting of two similar quarter-parts 14 and 15 and a half-part or cover 16.

The two base parts 14 and 15 of the coil housing engage the opposed faces of the exposed portion of laminated core 12, thereby forming a sort of cradle for the coil. These parts of the housing are preferably secured to each other and to the coil assembly by means of rivets 17 which extend through transverse openings in core 12. Cover 16 encloses the remainder of the coil body and is secured to parts 14 and 15 by means of rivets 18 or other suitable means.

Cover 16 is formed with a hollow boss 19, which is open at one end to receive the socket of a plug and socket connector for a high tension output terminal and is open at the other end to receive the socket 20 of a low tension plug and socket connection for the incoming current at primary generated voltage. Socket 20 may be of the well-known "Cannon" plug type and is secured in position by screws 21. The conducting element 22 of said socket is connected by means of an insulated lead 23 to one end of the primary winding of coil 10 for conducting current to the coil from a suitable source of electrical energy, such as from a battery or the coil of a magneto-generator. The socket for the high tension or output terminal of the coil is adapted to receive a suitable terminal of a high voltage conductor and comprises an insulating tube 24 having a slot 25 adjacent the inner end thereof in the side adjacent to coil 10. The lower end of tube 24 preferably rests on an insulating block 26, which is seated on a shoulder 27 in boss 19 of cover 16.

Novel means adapted for facilitating the assembly of the housing around the coil and for minimizing the danger of flash-overs within the coil housing are provided for connecting the output end of the secondary winding 28 of coil 10 to a terminal in socket tube 24. In the form shown, said connecting means and terminal comprises a perforated bracket 29 of relatively rigid metal having a spool-like portion 30 by means of which it is secured to coil casing 13. The end of secondary winding 28 may be connected in any suitable manner to spool portion 30. The perforated, laterally-projecting portion of bracket 29 extends through slot 25 in tube 24 and is engaged by a hook 31 on the lower end of a light coil spring 32. The width of the projecting arm

of bracket 29 is preferably sufficient to prevent any material angular movement of tube 24 around its own longitudinal axis.

The upper end of spring 32 has a straight centrally-disposed portion 33 which extends through a metallic tube 34 and is soldered or otherwise suitably secured thereto. A coil spring 35, which serves as a resilient contact for the connector plug (not shown) adapted to be extended into tube 24, has the lower turn thereof in close engagement with the outer wall of metallic tube 34 between a flange 36 formed on the tube intermediate the ends thereof and a washer 37 which fits over said tube and engages an internal shoulder in socket 24 against which it is yieldably held by spring 32. Washer 37 and the turn of spring 35 around tube 34 are clamped in place against flange 36 by spinning the lower end of said tube against the lower face of said washer. When the parts are assembled in the positions illustrated, spring 32 is preferably under slight tension so as to hold the parts in assembled relation.

The adjacent ends of the primary and secondary windings of coil 10 may be grounded in the usual manner by connecting the same to a portion of housing member 15, such as by means of a set screw 38. The free space within housing 14, 15, 16 is preferably filled with an insulating compound 39. Polymers of cashew-nut-shell oil and linseed oil have been found suitable for this purpose, the same being injected through suitable openings, such as at 39a, into the assembled housing in liquid form with the aid of vacuum and/or pressure. The compound may be injected at one of the openings 39a while the other serves as a bleed port for the expulsion of air. The filling compound is preferably supplemented with a drying agent so that it will set to a solid form by chemical reaction without the presence of oxygen. Setting of the filler may be facilitated by suitable heating. During the filling process, that portion of socket 24 above washer 37 may be filled with a removable plug. Any filling material which does enter this socket may be readily removed either before or after the compound has set.

Coil 10 and core 12, the latter of which forms the magnetic flux path for the coil, are preferably assembled in a novel manner comprehended by the present invention. The coil is first wound on a tube of paper or like material (not shown) and the laminations of the core are thereafter installed. For this purpose, each lamination of the core is preferably originally formed as a solid or continuous rectangular or other suitably shaped piece and then cut at 40 without removing any appreciable amount of metal to permit the installation thereof on the wound coil. The resulting lamination is accordingly in the form of an elongated strip of flexible metal, the strip having turns or bends therein so that the ends thereof are adjacent each other. In the form shown, each lamination consists of two parallel, longitudinally extending arms 46 and 47 and two radially extending arms 48 and 49 with cut 40 between the ends of arms 46 and 48. The desired number of laminations are installed one or more at a time in the completed coil by bending or flexing the same so that the end portion or arm 46 thereof may be passed through the central opening of the coil, i. e., through said paper tube or the like. If desired, the core laminations may be so formed that the external or exposed portion of the core as installed will extend completely around the coil instead of around only half of the latter as shown.

If the characteristics of a solid or closed core

are desired, adjacent laminations are installed with the cuts 40 thereof at opposite ends of the coil, as shown in Fig. 4. If, on the other hand, a small gap is desired in the core or magnetic flux path to effect a more rapid dissipation of the residual flux therein after each excitation, the cuts or gaps 40 of all the laminations may be superimposed or made to coincide at the same end of the coil and, hence, provide the desired gap. In the latter instance, it may be desirable to remove some material when making the cuts 40, the amount to be removed depending upon the width of the gap desired. The choice of these two constructions will depend upon the particular engine on which the coils are used and whether successive excitations of the transformer coil are of the same or opposite polarity.

Novel means are also provided whereby the housed coil, as heretofore described, may be satisfactorily mounted on a hollow tube surrounding a valve rod or the like on an engine. As shown, parts 14 and 15 of the coil housing have two pairs of lugs 41 formed integrally therewith, the adjacent faces of said lugs being arcuate for engaging one side of said hollow tube. Flexible metal straps 42 engage the other side of said tube and are anchored to housing cover 16, such as by means of nuts 43, that engage the threaded ends of said straps and serve to tighten the same.

In order to avoid the possibility of crushing the tube on which the coil unit is mounted, rigid U-shaped elements 44 are interposed between straps 42 and said supporting tube and the edges thereof are in alignment with the edges of lugs 41 to thereby definitely limit the pressure which can be applied to the supporting tube by straps 42. A resilient pad 45 (Fig. 2) is preferably placed between the mounting tube and lugs 41. The thickness of pad 45 should be sufficient to necessitate some compression thereof before the edges of spacer elements 44 engage the edges of lugs 41. A satisfactory clamping pressure is thus assured without running the risk of crushing the mounting tube.

There is thus provided novel housing means for a transformer coil whereby the same is thoroughly protected from damage by the elements, shock, vibration, oil, heat, or otherwise and whereby the same may be adequately and safely secured to an engine in an advantageous and accessible position. Novel means for electrically connecting a housed coil to a high tension terminal within the housing are also provided whereby installation of the housing around the coil is facilitated and danger of improper or faulty installation is substantially eliminated. Additionally, there is provided a novel, simplified transformer coil and core assembly which is flexible and reliable in use and which may be rapidly and inexpensively manufactured in accordance with a novel method of manufacture comprehended by the invention.

Although only a single embodiment of the invention has been illustrated and described in detail, it is to be expressly understood that the same is not limited thereto. Changes may be made, for example, in various details of the design and arrangement of parts illustrated and other suitable materials may be used in lieu of the filling compounds mentioned. Other changes which do not depart from the spirit and scope of the invention will now be apparent to those skilled in the art. For a definition of the limits of the invention, reference is had primarily to the appended claims.

What is claimed is:

1. In apparatus of the class described, a tubular coil of electrically conductive material, an insulating casing around said coil, laminated metallic means forming a magnetic flux path around a portion of said coil, each lamination of said means being constituted by an elongated strip having bends therein so that the ends thereof are adjacent each other, one end portion of each of said laminations extending through the central opening in said coil, a metallic housing cooperating with the exposed portion of said laminated means for enclosing said coil and casing, a socket in said housing including a tube of insulating material adjacent to and extending longitudinally of said coil, a terminal in said tube intermediate the ends thereof, and means for connecting said terminal to one end of said coil including rigid conducting means secured to said casing and extending through a slot in one side of said tube for limiting angular movement of the latter and an extensible resilient conductor for mechanically and electrically connecting said terminal and said conducting means within said tube.

2. In apparatus of the class described, an ignition coil having primary and secondary windings, an insulating casing for said coil, a metallic housing enclosing said coil and casing, a socket in said housing including an elongated tube of insulating material for receiving a plug connector, terminal means in said tube intermediate the ends thereof, and means for connecting said terminal means to the high potential end of said primary winding including rigid conducting means secured to said casing and extending through an opening in one side of said tube for limiting angular movement of the latter and extensible resilient means mechanically and electrically connecting said terminal means and said rigid conducting means within said tube.

3. In apparatus of the class described, a coil, an insulating casing for said coil, a substantially closed core extending through said coil and surrounding a portion thereof for forming a magnetic flux path, a pair of housing members cooperating with the exposed portion of said core and secured thereto, a third housing member secured to said pair of members, whereby said coil is completely enclosed, a socket in one of said housing members, said socket including an elongated tube of insulating material adjacent to and extending longitudinally of said coil, terminal means in said tube intermediate the ends thereof, and means for electrically connecting said terminal means to one end of said coil including relatively rigid conducting means secured to said casing and extending through one side of said tube and extensible resilient conducting means mechanically and electrically connecting said terminal means to said rigid conducting means within said tube.

4. In apparatus of the class described, a coil, a metallic housing enclosing said coil, a socket in said housing including an elongated tube of insulating material, terminal means in said tube intermediate the ends thereof, and means for connecting said terminal means to one end of said coil including conducting means extending from said coil into said tube and extensible resilient means mechanically and electrically connecting said terminal means and said conducting means within said tube.

5. In apparatus of the class described, a coil, a metallic housing enclosing said coil, a socket

in said housing including an elongated tube of insulating material, terminal means in said tube intermediate the ends thereof, means for connecting said terminal means to one end of said coil including conducting means extending from said coil into said tube and extensible resilient means mechanically and electrically connecting said terminal means and said conducting means within said tube, and a filler of solid insulating material filling the space within said housing and tube inside said terminal means.

6. A transformer comprising a casing, a transformer coil within the casing, an interiorly insulated hollow boss on the casing, means comprising a lead and a conducting element connected to the low tension winding of said coil and extending into one part of said hollow boss, a filler of insulating material within said hollow boss and surrounding said lead and said element, a bracket electrically connected to the high tension winding of said coil projecting within the hollow boss, a metal washer supported within the hollow boss, a tensioned spring connecting the bracket and washer, a filler of insulating material within said hollow boss and surrounding said bracket and said spring, and spring contact means carried by the washer within the boss.

7. A transformer comprising a casing, a transformer coil within the casing, a hollow boss on the casing, means connecting the low tension winding of the coil with an electrical connection, means connecting the high tension winding of the coil with the interior of the boss, a contact within the boss, a tensioned spring connecting said contact and said high tension connecting means, and a filler of insulating material filling the space within the boss about said spring.

8. Means for connecting the winding of a transformer to a cable contact comprising a tubular member having a connection to the transformer winding extending therein and a cable contact spaced from said connection, means to close the tubular member at the said contact, a spring under tension connecting said contact and said connection, said tubular member containing and said spring being set in insulating material.
